His Attorney.

UNITED STATES PATENT OFFICE

CHARLES A. HOXIE, OF ALPLAUS, NEW YORK, ASSIGNOR TO GENERAL ELECTRIC COMPANY, A CORPORATION OF NEW YORK

MOTION PICTURE-SOUND APPARATUS

Application filed February 25, 1930. Serial No. 431,308.

My invention relates to apparatus for producing sound accompanied motion pictures and to that type of such apparatus in which the pictures and the sounds are produced by separate motor driven units.

The use of separate picture projecting and sound producing units adapted for simultaneous operation and each having its own constant speed driving motor has certain well known advantages over combined motion picture-sound producing apparatus such as is now in common use. The two units of the apparatus are adapted to reproduce from separate records and, having been started to reproduce their respective records synchronously, to continue to do so inasmuch as they are driven by constant speed motors. The two units, however, being of an entirely different construction from each other, impose loads of a different character on their respective motors; moreover the two motors even though they be of the same type and rating, may differ materially in their starting characteristics. For these reasons it has been found that even though corresponding portions of the two records are arranged at the reproducing point of the respective units preparatory to starting, it often happens that one unit will come up to speed before the other and destroy the synchronization. It is the object of my invention, therefore, to provide improved apparatus of this character having means for keeping the two units in proper speed relation at starting.

In carrying out my invention I provide a shaft for connecting together the rotating parts of the two units during the starting interval and provide means for automatically disconnecting the shaft from the units after the units have come up to full speed.

My invention will be better understood from the following description taken in connection with the accompanying drawing, and its scope will be pointed out in the appended claims.

In the single figure of the drawing which represents in a more or less diagrammatic way an embodiment of my invention, I have shown at 1 a motion picture projector having a synchronous driving motor 2 and at 3 a

sound reproducer having a synchronous driving motor 4. Between the two motor shafts is a connection comprising the flexible shaft 5 which is adapted to be operatively connected with the shaft of motor 2 through the clutch 6 and to be connected with the shaft of motor 4 through clutch 7. Each clutch is provided with an operating lever 8 by which the clutch is moved into engaging or disengaging position and each lever 8 is provided with a pair of operating electromagnets 9 and 10, the former serving to move the clutch into the engaging position and the latter serving to move the clutch into disengaging position. At some point between the two clutches there is provided a contact operating mechanism comprising the base 12 having arms 13 and 14 forming shaft bearings. Between these bearings is the screw 15 shown connected at opposite ends with the shaft 5 and clutch 6 and engaging this screw is the nut 16, a portion of which slides on the guide rod 17. Projecting from the nut is finger 18 which after the nut has been moved a predetermined distance by the screw engages the switch 20 to cause it to break contact with the fixed contact 21 and to make contact with the fixed contact 22. Circuit connections are made between the switch 20, the contacts 21 and 22 and the electromagnets 9 and 10 whereby current from a suitable source such as the battery 23 may energize either the magnets 9 or the magnets 10. The two motors 2 and 4 are shown connected to the same source 24 through the switch 25.

Supposing that the two machines are to be started for the synchronous reproduction of separate picture and sound film records, the film of each machine will be set with corresponding portions thereof at the reproducing point of each machine. With the two clutches 6 and 7 in engaging position the circuits of two motors 2 and 4 will simultaneously be closed. Any tendency of one motor to gain or lose speed relative to the other will be checked by the shaft connection so that both motors and hence the films driven thereby will move during the starting operation in absolute synchronism. During the starting movement the nut 16 will be

5 moved along the screw 15 so that by the time the motors have attained full synchronous speed the finger 18 will have moved the switch 20 to deenergize the clutch closing magnets 9 and close the circuit of the clutch opening magnets 10. The clutches, thereupon, are immediately shifted to disconnect position and the connecting shaft comes to rest. The two machines, however, continue 10 to operate in synchronism. To reset the nut for a subsequent starting operation the connecting shaft and screw may be rotated in any suitable manner as by hand. If desired, the nut 16 may be in the form of a half nut 15 which is yieldingly held against the screw so that it may be withdrawn and shifted lengthwise of the screw for resetting.

20 I have chosen the particular embodiment described above as illustrative of my invention and it will be apparent that various modifications may be made without departing from the spirit and scope of my invention, which modifications I aim to cover by the appended claims.

25 What I claim as new and desire to secure by Letters Patent of the United States, is:

30 1. In combination, a motor driven motion-picture projector, a separate motor driven sound reproducer, means for connecting together the moving parts of the projector and reproducer, and means operative in response to a predetermined starting movement of said parts for rendering the connection inoperative.

35 2. In combination, a motor driven motion-picture projector, a separate motor driven sound reproducer, flexible means for connecting together the moving parts respectively thereof during starting and means responsive to a predetermined rotative movement of said flexible means for interrupting said connection.

40 3. In combination, a motion-picture projector having a constant speed driving motor, a sound reproducer having a constant speed driving motor, means for simultaneously energizing said motors, rotative means connecting together the moving parts of said projector and reproducer, and means responsive to a predetermined rotative movement of said connecting means for rendering the connecting means inoperative.

45 4. In combination, a motion-picture projector having a synchronous driving motor, a sound reproducer having a synchronous driving motor, means comprising a flexible shaft and a clutch for connecting together the moving parts of said machines at starting, and means responsive to a predetermined rotative movement of said connecting means for causing the disconnection of said clutch.

50 5. In combination, a motion-picture projector having a synchronous driving motor, a sound reproducer having a synchronous driving motor, means for simultaneously

55 closing the circuits of said motors, a shaft, clutches for connecting the ends thereof with the respective motor shafts, electromagnetic means for opening said clutches, and contact means operated by the rotative movement of said shaft for controlling said electromagnetic means.

60 In witness whereof, I have hereto set my hand this 24th day of February, 1930.

CHARLES A. HOXIE.
